US0D1113812S

(12) **United States Design Patent** (10) **Patent No.:** **US D1,113,812 S**
(45) **Date of Patent:** **** Feb. 17, 2026**

(54) **HEADPHONES**

(71) Applicant: **Yiren Luo**, Shantou (CN)

(72) Inventor: **Yiren Luo**, Shantou (CN)

(**) Term: **15 Years**

(21) Appl. No.: **29/994,810**

(22) Filed: **Mar. 23, 2025**

(51) **LOC (15) Cl.** **14-01**

(52) **U.S. Cl.**

USPC **D14/223; D14/372**

(58) **Field of Classification Search**

(57) **CLAIM**

The ornamental design for headphones, as shown and described.

DESCRIPTION

FIG. 1 is a perspective view of headphones showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof; and

FIG. 9 is a left side view of the headphones in use; and,

FIG. 10 is left side view of the headphones in use, in an alternate configuration.

The broken line showing of a silhouette in FIGS. 9 and 10 is included for the purpose of illustrating environment and forms no part of the claimed design. All other broken lines in the drawings depict portions of the headphones that form no part of the claimed design.

1 Claim, 10 Drawing Sheets
